JAMES S. REEDER, OF PORTLAND, OREGON.

CARBURETER.

1,092,079.

Specification of Letters Patent. Patented Mar. 31, 1914.

Application filed June 3, 1913. Serial No. 771,559.

To all whom it may concern:

Be it known that I, JAMES S. REEDER, a citizen of the United States, and a resident of the city of Portland, county of Multnomah, and State of Oregon, have invented a new and useful Improvement in Carbureters, of which the following is a specification.

My invention relates to carbureters of the type which produce the fuel mixture by passing a current of air over an atomizer, or other fuel-oil feeding device, so as to cause the air to become charged with oil vapors.

As is well known, the difficulty generally experienced in carbureters is the obtaining of a properly balanced intermixture of gas and air. To accomplish this result, means have been provided for increasing the volume of air when a strong suction has a tendency to cause an excess of oil vapor. But such means, on the other hand, have a tendency to admit an excessive volume of air which must be balanced by a larger volume of oil vapor. Hence the purpose of my invention is to provide means whereby the oil feed is automatically controlled by the speed of the engine.

I attain my purpose by using for the control of the flow of fuel-oil into the atomizer, or other fuel-oil feeding device, located in the mixing chamber, a valve controlled by means operating like a centrifugal governor, and using the suction of air through the mixing chamber, induced by the charging stroke of the engine, as the force for actuating the governor.

I accomplish these and other incidental objects by the use of the devices illustrated in the accompanying drawings, in which:

40 Figure 1 is a vertical section of my carbureter, showing also a portion of the manifold leading to the engine cylinders, and the feed pipe connecting with the fuel storage tank; Fig. 2 is a horizontal section taken approximately on the line 2-2 of Fig. 1; and Fig. 3 is a detail of the needle valve showing the port which prevents said valve being entirely closed when the needle is seated.

50 The shell, *a*, of my carbureter is made with a lower flange *b*, an upper flange *c*, and an exterior water-jacket *d*, the outlet and inlet of which are not shown in the drawings. The lower end of the shell, *a*, is further provided with an interior collar *e*, which forms a seat for a cylinder *f*. A float

chamber *g* is provided on its upper end with a flange *h*, which abuts against the flange *b*, the two flanges being bolted together by the bolts *i*. To insure a tight joint the gasket, *j*, is used. The float chamber *g* is of annular form, the interior and open portion, *k*, connecting the cylinder, *f*, with the atmosphere. A centrally located bearing *m* is supported in axial alinement with the cylinder, *f*, by the arms *n*, the latter extending from the walls of the annular opening *k*. The upper end of the bearing, *m*, is open, the lower end is closed except for a hole through which the stand-pipe, *o*, extends, 65 and an agate bearing, *p*, is mounted on the inner face of said bearing *m*. The pipe, *o*, forms a direct connection between the float chamber, *g*, and the bearing *m*. See Fig. 1. Said pipe extends upwardly some distance 70 above the lower end of the cylinder *m*, so that the gasoline will not overflow. A feed pipe, *q*, connects the fuel tank (not shown) with the interior of the float chamber *g*. A float, *r*, which should be visible through 75 some convenient glass indicates the amount of fuel present in the float chamber at any time. See Fig. 1.

A valved connection regulates the flow from the pipe *q* into the float chamber, as 85 follows: A needle, *20*, is mounted on an arm, *21*, the latter pivotally mounted between the ears *22* on the floor of the float chamber. A spring, *23*, normally holds the needle down, thereby closing the valve and 90 cutting off the inflow. The arm, *21*, is provided with a bifurcated end, the members, *24*, of which bear against the lower surface of the floor *r*. As the gasoline in the float chamber is drawn out through the pipe *o*, 95 the float, *r*, will drop to a lower level, depressing the arms *24*, and thereby elevating the needle *20*. The inflow of gasoline from the feed tank will then raise the float, *r*, and cause the needle *20* to again close the 100 valve. In this way, a constant supply of fuel is maintained in the float chamber and is prevented from overflowing the pipe *o*.

The cylinder, *f*, is adapted to be inserted inside the shell, *a*, and is held in place on the 105 collar *c*. Said cylinder is further provided with inwardly extending, obliquely inclined deflector-wings, *t*, as shown in Figs. 1 and 2.

A cylindrical body, *u*, made with a coned portion *v*, and a cylindrical lower end *v'* of decreased diameter is inserted in the cylinder *f*, so that said lower end *v'* will bear 110

in the agate ring bearing p . The body, u , is hollow and is made with a needle valve opening at its lower end, the portion of the lower end below the needle valve opening being cored out so as to form a hood for the end of the pipe o . The body u , is provided with radially projecting exterior wings w , lying in oblique planes, an inner collar w' , and outlet orifices x , see Fig. 1. A needle, y , normally seats itself in the valve opening in the lower end of the body u . Said needle is made with a port y' at its lower end. See Fig. 3. In this way, the valve will never be entirely closed. A perforated disk, 4, dropped over the shank of the needle, y , will seat itself in the coned portion, v , and act as a bearing for said needle. A second disk, 5, dropped over the shank of the needle, will seat itself on the collar w' . Mounted on the disk, 5, are two pairs of diametrically opposed ears 6. Pivotally mounted in each pair of ears is a bell-crank 7, each bell-crank being made with weighted upper arms, and the lower arms being formed as toes which project under a collar 8, the latter being pinned onto the shank of the needle y . These bell-cranks act as ball governors to raise or lower the needle y . A coil-spring 9, encircling the shank of the needle y , bears on the collar 8 and normally holds said needle in its lowermost position. A plug end, 10, adapted to fit the upper end of the body u , forms a bearing for an adjusting screw 11, the latter being made with an enlarged cylindrical bottom, 11², cored out so as to fit over the spindle of the needle y , and adapted to bear on the coil-spring 9. A head, 11', on the upper end of the screw, 11, affords a convenient means for turning the latter. By turning the screw, 11, the spring 9 may be compressed to any desired degree. A collar, 12, fast on the plug-end, 10, is provided with an annular groove containing the ball-bearings 13. A ring 14, supported by the arms, 15, resting on the upper end of the cylinder f encircles the collar 12 and provides a bearing surface for the bearings 13. The flange, c , of the shell, a , is bolted to the flange of the manifold, 16, a gasket, c' , being placed between the flanges to insure a tight joint. A hand-hole 17 in the manifold, 16, provides a means of easy access to the adjusting screw 11.

The action of my carbureter is as follows: The spring 9 will normally hold the needle y in its lowermost position. A certain amount of oil vapor will rise through the port, y' , into the body u , so that when the engine is turned over, the draft created through the manifold, 16, will suck the oil vapor out through the orifices, x , of the body, u , into the manifold to the engine cylinders. The continual suction through the manifold, when the engine is running, will draw a current of air up through the central

opening, k , of the float-chamber g . This current of air will strike the wings, t , and be deflected against the fans, w , with the result that the body, u , will be given a rotary motion in its bearings p , 13. As the speed of the engine increases, the rotary speed of the body, u , will also increase and the resultant partial vacuum created in the body, u , will suck the fuel up through the port y' . The partial vacuum in this case is formed by the centrifugal throw of the air out through the orifices x . When the engine speed has reached a certain point, the ball-governors, 7, will be thrown outwardly, thereby raising the needle, y , and allowing a freer feed to be made through the valve opening. After a predetermined speed of the engine has been reached, the ball-governors will contact with the walls of the body u , and any further opening of the valve will be prevented. Therefore, for any higher speed of the engine, the same opening of the inlet valve will be maintained. In this way, the mixture of air and oil vapor will be controlled automatically by the speed of the engine, and no adjustments from the throttle will be necessary.

I claim:

1. In a carbureter of the type specified, a mixing chamber, a fuel-oil feed having an outlet located in such chamber, a valve element consisting of a valve case rotatably supported in said mixing chamber, such valve being mounted on said outlet, said case being provided with an inlet orifice and an outlet orifice, a valve controlling such inlet, a centrifugal governor for such valve within the valve-case, and means whereby the air sucked through the mixing chamber is caused to impart rotary motion to said valve.

2. In a carbureter of the type specified, a mixing chamber, a fuel-oil feed having an outlet located in such chamber, a valve element consisting of a valve case rotatably supported in said mixing chamber, such case being mounted on said outlet of the oil feed and being provided with an inlet orifice and an outlet orifice, said valve having a stem longitudinally movable in the valve case, means for yieldingly holding the valve on its seat, a centrifugal governor in the valve case, such governor being connected with said valve stem, and means on the exterior of the valve case and the interior of the mixing chamber whereby the suction of air through the latter is caused to impart rotary motion to the valve case.

3. In a carbureter of the type specified, a mixing chamber, a fuel-oil feed having an outlet located in such chamber, a valve element consisting of a valve case rotatably supported in said mixing chamber, such case being mounted on said outlet of the oil feed and being provided with an inlet orifice and

an outlet orifice, said valve having a stem longitudinally movable in the valve case, adjustable means for yieldingly holding the valve on its seat, a centrifugal governor in the valve case, such governor being connected with said valve stem, and means on the exterior of the valve case and the interior of the mixing chamber whereby the

suction of air through the latter is caused to impart rotary motion to the valve case. 10
